UNITED STATES PATENT OFFICE.

ROY D. KING, OF CHICAGO, ILLINOIS.

SHINGLE-CUTTING MACHINE.

1,394,911.

Specification of Letters Patent. Patented Oct. 25, 1921.

Application filed November 1, 1920. Serial No. 420,936.

To all whom it may concern:

Be it known that I, ROY D. KING, a citizen of the United States, residing at Chicago, in the county of Cook and State of Illinois, have invented certain new and useful Improvements in Shingle-Cutting Machines, of which the following is a specification.

This invention relates to machines for cutting strips of shingles from a sheet of composition roofing. By means of the machine, the sheet of roofing is severed transversely into shingle strips, the lower edges of which are provided with spaced recesses simulating in appearance the spaces between the individual wooden shingles of a roof when laid in rows in the customary manner. When the strips produced by this machine are laid in horizontal overlapping rows, the exposed portion separated by the recesses closely resemble the shingles of a wood shingle roof.

While I am aware that machines for this general purpose have heretofore been devised, the primary purpose of my present invention is the provision of a machine in which all of the operations are cutting, as distinguished from tearing operations, so that all of the edges of the shingle strip will be smooth and even, thereby producing shingle strips, the upper edges of which are straight and smooth, and the lower edges of which simulate the appearance of wooden shingles laid in spaced relation.

Another object of my invention is to provide a machine of the character indicated, which will be capable of adaptation to produce a variety of shingle shapes by simply changing the form of the stationary cutting block and the complementary movable cutter which coöperates therewith.

Another object is to produce a machine which, instead of first removing the waste from the upper edge of a shingle strip and then severing the strip from the sheet of material, will first sever a shingle strip from a sheet, forming during this cutting operation the lower edge of the shingle strip, and then subsequently cutting the waste from the upper edge of the strip after it has been severed from the sheet, thereby producing a smooth upper edge for the strip and completing the formation of the strip.

For the purpose of facilitating an understanding of my invention, I have illustrated on the accompanying drawings, one practi-

cal and preferred embodiment thereof, from an inspection of which the construction, mode of operation, and many of its inherent advantages should be readily understood 60 and appreciated.

Referring to the drawings:

Figure 1 is a longitudinal sectional view, somewhat diagrammatic in character, illustrating the novel features of a machine embodying my invention; 65

Fig. 2 is a plan view of the structure shown in Fig. 1;

Fig. 3 is a detail plan view of the stationary cutting block; and 70

Fig. 4 is a detail plan view of a finished shingle strip.

The machine embodying my invention comprises a supporting frame of suitable construction upon which the operating 75 mechanisms are mounted, the side portions of the frame being designated generally in Fig. 2 by reference character 5. Within the frame, there is mounted a transversely extending spindle beam 6 adapted to carry 80 a roll 7 of composition roofing material which is fed therefrom into position to be cut into shingle strips by a pair of feed rollers 8 and 9 driven by any suitable mechanism (not shown).

Forwardly of the feed rolls there is mounted upon a suitable rigid support 10, a stationary block or die 11, formed on its rear edge to provide alternately disposed recesses 12 and projections 13, the projections being of the width of the desired spaces to be produced in the lower edge of a complete shingle strip, one of such shingle strips being shown in Fig. 4, and indicated generally by reference character 14. 95 It will be observed from this figure that the upper edge 15 of the strip is straight while the lower edge which projects beyond the next overlapping layer when the strips are laid on a roof is provided at spaced intervals with recesses 16 which resemble in appearance the spacing between the shingles of a wooden roof. In order that this spacing may be uniform, the stationary block 11 is so designed that one half of a recess 105 is cut at each end of the shingle strip as indicated by reference character 17 so that when two strips are laid end to end, a space equal to one of the spaces 16 is formed between the ends of the strips.

Upon a stationary shaft 18, mounted in the frame of the machine forwardly of the block

11, there is rotatably mounted a movable cutter 19, the cutter being of generally U-shape, and provided with bearings 21 and 22 which rotate upon the shaft 18, power being applied through a belt pulley 23 or other suitable means.

The outer edge of the cutter is shaped to provide recesses 24 and projections 25 complementary to the projections 13 and recesses 12 of the stationary block, the block and cutter each presenting a plurality of complementary cutting edges so that when the cutter is moved downwardly across the block, a shingle strip will be severed from the sheet 15 of material 26 with the lower edge of the strip completely formed and provided with the spaces 16 and 17. Those portions of the sheet lying upon the arms 13 will be left as projections upon the upper edge of the next 20 succeeding shingle strip and the rate of feed of the sheet by the feed rolls relative to the speed of rotation of the cutter 19 is such that while the cutter is making a complete revolution, the sheet will be fed forwardly 25 substantially into the position shown in Fig. 1.

The cutter 19 is provided, a distance from the ends of the projections 25 equal to the width of a complete shingle strip, with a 30 straight cutting edge 27, which, as the cutter moves downwardly to sever a shingle strip from the sheet, engages the forward edge of the severed strip just at the base of the waste portions projecting from the forward edge 35 of the strip. Beneath the plane of the stationary block 11, there is mounted a die or block 28 having a straight cutting edge 29. This block is preferably fixed upon the shaft 18 and its width is equal to the length of 40 the projecting waste so that when the severed shingle strip is carried downwardly by the rotating cutter 19, the coöperative action of the cutting edges 27 and 29 sever the waste projecting from the upper edge of 45 the shingle strip, thereby leaving a straight, smooth, upper edge, as shown in Fig. 4. These projecting waste portions are indicated in Fig. 2 by reference character 31. Upon further movement of the cutter 19, the 50 completed shingle strip is delivered on to a carrier from which it is conveyed from the machine while the waste portions drop upon another conveyer, by which they are delivered from the machine. In some instances, 55 instead of having the block 28 stationary, it may be mounted to rotate upon the shaft 18 in a clockwise direction, while the cutter 19 is rotating in counter-clockwise direction. The operation of cutting off the waste would 60 be substantially the same in either instance, but the waste cut off by the rotating block 28 would be carried on over the shaft 18 and delivered forwardly of the shaft instead of rearwardly thereof as in the construction 65 disclosed in which the block 28 is stationary.

It will be apparent from the foregoing that by my machine, a shingle strip is first cut from a sheet of roofing material so as to form the spaced recesses at its lower edge and subsequently the projecting fingers or waste portions at the upper edge of the strip are removed therefrom as the strip is carried downwardly by the revolving cutter 19.

While I have illustrated the stationary block and revolving cutter as constructed 75 to produce shingle strips of the character disclosed in Fig. 4, it will be manifest that shingle strips having variously shaped lower edges may be produced by my machine by simply changing the form of the stationary 80 block and making the movable cutter complementary thereto, whereby any desired configuration of shingle strip may be produced. The details of construction of the machine may obviously be varied within 85 wide limits without departing from the spirit of the invention as defined in the following claims.

I claim:

1. A shingle cutting machine, comprising 90 a stationary block having alternately disposed recesses and projections over which the sheet of material to be cut is fed, a movable cutter having complementary recesses and projections coöperating with said block 95 to sever the lower edge of a shingle strip from said sheet, and means for subsequently removing the waste projecting from the upper edge of said severed shingle strip.

2. A shingle cutting machine, comprising 100 a stationary block provided with alternately disposed recesses and projections over which the sheet of material to be cut is fed, a movable cutter having complementary recesses and projections coöperating with said block 105 to sever the lower edge of a shingle strip from said sheet and also having a transversely disposed cutting edge spaced from the ends of the cutting projections a distance equal to the width of the shingle strip, and 110 means independent of said block coöperating with said transversely disposed cutting edge for severing the waste from the upper edge of said shingle strip after severance of said strip from said sheet.

3. A shingle cutting machine, comprising 115 a stationary block provided with recesses and projections over which a sheet of material to be cut is fed, a movable cutter having complementary recesses and projections coöperating with said block to sever a shingle strip from said sheet and also having a transverse cutting edge spaced from said 120 projections, and means coöperating with said cutting edge for removing the projecting waste from the upper edge of a shingle strip subsequent to the severance of said strip from said sheet.

4. A shingle cutting machine, comprising 125 a stationary block having a plurality of cut- 130

ting edges, a movable cutter provided with complementary cutting edges adapted to co-operate with said block to sever a sheet of material and also having a transversely disposed cutting edge spaced from said cutting edges, and means independent of said block for coöperating with said transverse cutting edge to remove the waste from the upper edge of a shingle strip severed from said sheet by the coöperative action of the cutting edges on said block and cutter.

5. A shingle cutting machine, comprising means for transversely severing a sheet of roofing material to produce a shingle strip having spaced recesses along its lower edge, the material removed from said recesses remaining as waste projecting from the upper edge of the next shingle strip, and means for removing the projecting waste from the

shingle strip subsequently to the severance 20 of said strip from said sheet.

6. In a machine for cutting composition shingles, the combination of a stationary cutting block, means for advancing a sheet of material over said block, means coöperating with said block to cut from the forward end of said sheet a shingle strip having spaced recesses at its rear or lower edge, the projections produced by forming said recesses remaining attached to the upper or forward edge of the next shingle strip to be cut, and means operable upon each shingle strip subsequently to its severance from said sheet for removing said projections from the forward edge thereof so as to produce a substantially 35 straight edge.

ROY D. KING.
